UNITED STATES PATENT OFFICE.

FRITZ EDLER VON EMPERGER, OF VIENNA, AUSTRIA.

COMPRESSION MEMBER FOR STRUCTURES.

1,412,096.

Specification of Letters Patent. Patented Apr. 11, 1922.

Application filed June 17, 1912. Serial No. 704,102.

(GRANTED UNDER THE PROVISIONS OF THE ACT OF MARCH 3, 1921, 41 STAT. L., 1313.)

To all whom it may concern:

Be it known that I, FRITZ EDLER VON EMPERGER, a subject of the Emperor of Austria, and residing at Dominikanerbastei 4, Vienna 5 I, Austria, engineer, have invented certain new and useful Improvements in Compression Members for Structures, of which the following is a specification.

This invention relates to cast iron compression members for structures and has for its purpose considerably to increase the compressive strength of such members by preventing, in a cheap way, the bulging which precedes buckling. According to the invention, 10 the members are constructed by surrounding the cast iron compression member, after having been brought into its position in the structure, with a wrought iron hooping, arranged at a given distance therefrom, and of sufficient tensile strength as to resist the radial strains produced by the tendency of the cast iron member to bulge, and by filling the interspace with a material adapted to be impressed by the said 15 strains and to transmit them to the hooping. The material used for this purpose is concrete. Of course, girders whose compression flange is reinforced in the manner referred to, fall within the scope of the invention.

In the annexed drawings, which form a part of this specification, Figs. 1 and 2 illustrate in sectional elevation and sectional plan, respectively, a compression member. 20 In said figures, the numeral 1 denotes a cast iron tube surrounded by an envelope of hooped concrete 2 denoting the helical windings, 3 the longitudinal reinforcing bars, and 4 the concrete.

This compression member for whatever purpose it may be applied, yields the effect that although cast iron is a brittle and inelastic material, the member as a whole formed as described of a cast iron core embedded in hooped concrete, possesses elastic properties and under compression behaves in a manner which cannot be obtained with a material of high elastic limit, such as mild steel. Owing to this property a more extended sphere of use is secured for cast iron and similar inexpensive materials of the kind hereinbefore mentioned, enabling these materials to be used in works for which they would previously have been deemed insufficiently reliable.

The spacing of the straps or windings of the hooping depends broadly on the manner in which the member is stressed, but the above mentioned static effect is obtained when the said spacing is approximately 60 equal to the thickness 6 of the concrete envelope measured from the cast iron core to the transverse reinforcement. The thickness of concrete outside the hooping does not come into consideration for the static 65 effect, and may be looked upon as merely a fire proof dressing and also prevents rusting of the windings 2 and rods 3.

Fig. 3 illustrates in sectional plan a modification of the last described compression 70 member, in which the core consists of a solid bar 7 of cast iron of circular cross section for example, instead of the tube of Figs. 1 and 2.

Fig. 4 illustrates an adaptation of the 75 compression member to an arch, which may have a crown joint. Fig. 6 is a cross section on A—A of Fig. 4 and Fig. 5 a corresponding sectional elevation. The section on the line B—B of Fig. 4 may have any of the three 80 forms illustrated in Figs. 7, 8 and 9. As will be seen in these figures, three compression members I, II and III of the above described type are arranged adjacent to each other at the abutment of the arch and are bound together by means of the concrete and if necessary also by means of connecting irons. As these three compression members rise towards the crown of the arch, the middle member II is displaced above the plane of 90 the other two. These compression members might also converge towards the crown of the arch as shown in Fig. 8 or be consolidated into a single solid bar as shown in Figs. 3 and 9, in both of which cases, instead 95 of each tube having its own hooping, the hooping may be common, to the three cast iron cores as shown in Figs. 8 and 9. Fig. 10 illustrates a further example of an arched bridge with three (or only two) joints, Fig. 11 showing the cross section at the position C—C. Fig. 12 the cross section at the position D—D, and Fig. 2 the cross section at the position E—E. It will be seen that the cast iron cores are combined close to the joints into a single tube branching into two tubes of semi-circular cross section, as shown in Fig. 11 the distance apart of which tubes gradually increases to the maximum shown in the cross section on D—D. The hooping 100

of the two tubes is always common to both and when their distance apart is large as in Fig. 12 cross reinforcing bars 8 between the tubes may be provided. The gradual diverging 5 of the cast iron cores in this case has the purpose of keeping the line of pressure inside the ellipse of inertia of the reinforced cross section.

In the example illustrated in Figs. 11 and 10 12 the spacing of the transverse reinforcement 2 of the concrete envelope may be equal to or smaller than the least thickness of the concrete envelope measured from the cast iron core to the transverse reinforcement.

15 In Fig. 13 is illustrated a bridge girder of which the cross section on the line F—F may be as shown in Figs. 14 or 15. The compression flange of this girder as shown in Fig. 14 consists of a solid cast iron bar of T 20 cross section embedded in hooped concrete, and in Fig. 15 of three rectangular cast iron tubes, the central one of which is of elongated downwardly extending cross section.

25 The three tubes are embedded in a cement envelope and have a common hooping. The hooping 2 also is reinforced by longitudinal bars 9, and transverse reinforcing bars 8 are provided between the tubes.

30 The strengthening of hooped compression members by means of cores of high compressive strength, as hereinbefore described, is not to be confounded with the known procedure of dressing cast iron columns with fire clay or even with cement concrete, as is 35 done in the case of smoke flues and the like, as this procedure merely yields a material of the same strength as concrete and serving as a protection to the reinforced concrete against chemical and heating effects. The

40 reasons why materials of such high compressive strength as cast iron have not been used alone in the making of long compression members, consists among others in that it is only possible to manufacture comparatively 45 short members in a single piece and that the uniting of several parts into a long member, apart from the danger of buckling, is attended with a loss in the transmission of the stress from one member to the other, and this 50 in combination with the unreliability of such built up members, renders the adoption of long built up members difficult or impossible.

If therefore structural members of considerable length such as pillars, columns, arches 55 and the like are to be made out of such materials, a reliable means of connection of the parts is necessary. The sources of loss just referred to will now be examined.

These losses arise in the first place owing 60 to the unavoidable inequalities at the joints or abutting surfaces. This circumstance, which cannot be obviated even by the most careful workmanship, has for result that the stress becomes concentrated at particular 65 places and the shearing forces thereby

created tend to split the whole member into vertical strips. In this manner a local failing may take place long before the actual compressive strength of the material has been fully developed.

70

Attempts have been made to overcome this drawback by carefully machining, fitting and polishing the joint faces, but the feasibility of such a procedure, is now generally recognized and a solution of the difficulty is sought in the provision of cushions or the like for ensuring uniform transmission of stress, for example cushions of sheet metal or lead, or tar. The advantage of the better transmission of the stress is 80 however impaired by the unavoidable softness of the cushion which becomes plastic even at moderate pressures and has a tendency to run out of the joints so that the aforesaid splitting into vertical pieces takes place and 85 is even accelerated. The drawback, caused by this reduction in strength depends upon the thickness of the joint, but when this latter is to fulfill its function, it must have certain minimum dimensions. The effect of the 90 cushioning substance becomes the more prominent the greater the difference in strength between the two constituents so that in the case of cast iron cores no substantial economy 95 or advantage is obtained. The same is also true of compression members containing an assemblage of cast iron tubes. In this case also a non-uniform transmission of stress is the cause of unreliability such that without exceptional precautions the building up 100 of compression members of several parts is not permissible.

100

The compression members according to this invention are adapted to be used with either single pieces of the cast iron or with 105 pieces which are to be assembled into a longer member. The invention has therefore also for object the application of less hard cushioning material of the type above referred to at the abutting faces of the different component members or core pieces in order to obtain a uniform transmission of the thrust from one member to another. As this cushioning material is also embedded in the hooped concrete, it is prevented from being forced away from its place of working, and also a splitting of the structure in vertical direction is obviated. Even if such a splitting should be given it would not be injurious since the unity of the cross section 110 115 is not impaired. It would moreover be of advantage to arrange a stronger transverse reinforcement at these joint positions and to increase the number of longitudinal bars, to avoid the danger of buckling. Several examples of such compression members are illustrated.

120

In Figs. 16 and 17, 1 denotes the core tubes which are only a fraction of the length of the compression member being 130

made, so that a number of such tubes must be arranged end to end to form one compression member. These tubes are surrounded by an envelope of hooped concrete 5 consisting of the hooping 2, the longitudinal bars 3, and the concrete 4.

At the joint places 10 of the tube sections there is provided a soft cushioning or jointing material such as lead, tar or the like for 10 the purpose of providing a uniform transmission of thrust from one tube section to the other.

As this material is prevented by the concrete envelope from being squeezed out from 15 between the jointing faces, its full effectiveness is ensured up to the full breaking load of the compression member. Any possible forcing out of the cushioning material into the hollow of the tubes can be prevented 20 by means of a short overlap of the latter at the internal periphery. In the case illustrated flanges 11 are also provided at the joints which flanges are screwed together by bolts 12. The transverse reinforcement 25 2 is shown heavier for a determined distance 13 near the joints, and in addition the number of longitudinal bars is increased by the provision of additional bars 14 for the purpose of diminishing the danger of buckling, 30 which in columns for example is most likely to take place at the middle. In the example illustrated the bars 14 consist of extensions of the connecting bolts 12 of the two flanges. The arrangement shown in Figs. 18 and 19 35 differs from the foregoing construction only in that solid bars of any desired cross section and of cast iron are used.

In the construction according to Figs. 16 to 19 the hooping of the concrete is shown 40 in the form of helical windings on the Considère system which is of advantage in such cases. As moreover the cross section of the core and that of the concrete envelope may have different profiles in some cases and especially when the hooped concrete envelope is 45 of great thickness, the transverse reinforcement cannot be arranged as in the foregoing examples, but the spacing 5 of the said transverse reinforcement must be equal 50 to the mean between the least thickness and the greatest thickness of the concrete envelope measured from the core to the transverse reinforcement. It is understood that the form of the cross section of the core may 55 be different from that of the concrete envelope, the hooping of the concrete however conforming as closely as possible to the cross section of the core.

The rational application of these methods 60 of constructing compression members for bridges will be evident from the foregoing description.

The improved compression members are 65 also intended to be applied in cases of combined stress, for example push and pull, that

is in cases of bending. For this purpose the member of solid bars or tubes of tubular cast iron bars, a wrought iron hooping surrounding them at a given distance, and an intermediate filling of concrete, is utilized 70 only in the compression flange or in the struts of the structure while in the tension flange or part of the structure subjected to the tension, the usual tension members of wrought iron or mild steel are used. If it 75 is intended that this reinforcement should constitute a resistive skeleton even without the concrete envelope in order to relieve the core and to render the same wholly or partly dispensable, the said reinforcement members must be mutually connected. This is 80 generally done at the ends of the reinforcing bars, while between the same, projections or extensions of the compression flange reinforcement extend into the tension flange and 85 support the tension bars. Further, it is also possible to embed the whole iron reinforcement in a hooped concrete envelope in order to still further increase the strength of the 90 structure element.

The tension bars, or the whole of the iron skeleton may if desired be given an initial tension.

Examples of the structure element intended for resisting push and pull stress are 95 shown, in the form of girders with solid web, jointed girders, such as trussed or square girders.

Fig. 20 is an elevation and Fig. 21 a cross section on the line G—G of a girder resting 100 on two supports and having in its compression flange a solid bar 1 of cast iron of suitable cross section and in one or several connected lengths. This solid bar is provided at a suitable distance therefrom with a 105 winding 2 or with embracing straps of wrought iron or mild steel. In the bottom flange of this beam there is provided the usual tension reinforcement 18, which in order to make a resistive skeleton of the 110 whole reinforcement without the presence of the concrete filling and envelope and thereby relieve the core from stress and render it partially or wholly dispensable, is connected 115 at its ends 19 with the compression reinforcement 1 in any manner for example by means of bolts 21. To obtain the necessary stiffness of the skeleton, projections 20 extend from the core 1 of the compression reinforcement to the tension flange which may 120 either be in one piece with the reinforcement 1 as on the left hand side of Fig. 20 or may be connected thereto as on the right hand side of Fig. 20. These projections 125 may also be surrounded by helical wire coils arranged at a given distance therefrom, as shown at the left in Fig. 20 and their purpose is to support the tension member at the points of bending. In this manner the two flanges are bound together into a self sup- 130

porting skeleton which may be given an initial tension as required. For this latter purpose it is only necessary to screw up the nuts 21 at the ends of the tension member.

5 With this construction it is also possible to surround the compression and tension flanges as a whole with a hooping arranged at a given distance therefrom, and either consisting of a helical wire winding, or with 10 straps 22 to increase the strength of the girder by resisting radial stresses. The hooping surrounding the cast iron and also that common to all the reinforcements may be an iron network of any suitable arrangement in which the tensile strength of the wire is rationally availed of; in the examples illustrated the longitudinal bars may be omitted. The network must be of such dimensions and of such size of mesh that 15 all the radial stresses arising within the cast iron core are with absolute certainty, transmitted to the hooping, which resists them. The concrete fills a double function. Its main purpose is to make the effect of 20 the hooping effective over the whole periphery of the cast iron. Under conditions, with suitable strength and thickness of the hooping iron, it is thus possible to reduce the distance between the windings and the 25 cores to a minimum. In the second place the compressive effect of the hooped concrete obviously comes into consideration only where there is a sufficient thickness of concrete. The provision of longitudinal 30 bars in the hooping is recommended at the 35 places of connection of the cast iron core, where such bars strengthen the connections of the component parts.

Figs. 22 and 23 show as further example a 40 portion of the girder structure in elevation and in cross section on the line H—H, in which the two flanges are connected to each other in known manner by means of compression and tension members. The compression member 23 consists in the cast iron core 1 surrounded in the hereinbefore described manner by helical wire hooping 2, arranged at a given distance from said core, and an interposed filling of concrete for the 45 transmission of the stresses. The tension flange 24 contains the usual tension bars 18 which are held together by straps 25 spaced at suitable distances. The connection of the two reinforcements 1 and 18 is provided also 50 in this case for the purpose of creating a self supporting skeleton without the concrete envelope, and which may if desired be given initial tension.

Fig. 24 illustrates a girder attached to a 60 column 26, that is with built in ends, whereby positive and negative moments are present, in consequence of which the compression reinforcement 1 goes at the column from the top flange to the bottom flange, and the

tension reinforcement 18, on the contrary, 65 from the bottom flange to the top flange.

In Figs. 25 and 26 there is illustrated in elevation and cross section on I—I a beam in which the cast iron compression reinforcement 1 is itself a trussed structure, while 70 the tension reinforcement 18, as in Fig. 20 attached to the bottom of the structure, is anchored at the ends of the same in such a manner that the tension member may be tensioned in order to impart an initial tension to the skeleton. Two wedges 27 as shown in Figs. 25 and 27 (a section on K—K), may be used for this purpose, the wedge being semi-circular form whereby the end of the tension bar may be passed round 75 the same and formed in a loop 28. To prevent slackening of the loop a wedge 31 is fitted within the same which is either effective only at the binding 32, or is of such length that it abuts against the same at one end and 80 against a block at the other end. The two wedges are connected by means of a bolt 29 and can be moved towards or away from each other along inclined surfaces 33 transversely to the girder for the purpose of tensioning or slackening the tension bars. In 85 the example illustrated these inclined surfaces are located on lateral projections 30 on the core or compression reinforcement, but they may be on the core itself. In this 90 case also the compression and tension reinforcement as a whole is surrounded by a hooping 22 keeping both parts in fixed position relatively to each other. There is also 95 provided the concrete, for the purpose above 100 described.

Having now described my invention, what I claim as new and desire to secure by Letters Patent is:

1. In a girder, the combination with a 105 tension flange, of a compression flange in which a cast iron core is surrounded at a given distance by a wrought iron hooping of sufficient tensile strength as to resist the bulging of the core under compressive 110 strains, and the space between the core and the hooping filled with concrete.

2. In a girder, the combination with a tension flange, of a compression flange in which a cast iron core is surrounded at a given distance by a wrought iron hooping of sufficient tensile strength as to resist the bulging of the core under compressive strains, and the space between the core and the hooping is filled with concrete, and of a wrought iron 120 hooping surrounding both flanges and filled with concrete.

3. In a girder, the combination with a tension flange, in which tension bars are embedded in concrete, of a compression flange, 125 in which a cast iron core is surrounded at a given distance by a wrought iron hooping of sufficient tensile strength as to resist the

bulging of the core under compressive strains, and the space between the core and the hooping is filled with concrete, and of adjustable connections between the tension 5 bars and the cast iron core.

4. In a girder, the combination with a tension flange, in which tension bars are embedded in concrete, of a compression flange in which a cast iron core is surrounded at a 10 given distance by a wrought iron hooping of sufficient tensile strength as to resist the bulging of the core under compressive strains, and the space between the core and the hooping is filled with concrete, of adjustable 15 connections between the ends of the tension bars and the ends of the cast iron core, and abutments for the tension bars, projecting from the cast iron core.

5. In a girder, the combination with a tension flange having tension bars embedded in concrete, of a compression flange in which a cast iron core is surrounded at a given distance by a wrought iron hooping of sufficient tensile strength as to resist the bulging 25 of the core under compressive strains, and

the space between the core and the hooping is filled with concrete, of wedges adjustable across the ends of the cast iron core and having the ends of the tension bars secured to them.

6. In a structure member, a compression flange consisting of a core piece of brittle material of high compressive strength embedded in an envelope of hooped concrete, a tension flange consisting of tension bars 35 exterior to said hooped concrete, wedges at the end of the core piece transverse to the same, inclined surfaces on the core piece with which the said wedges co-operate, and means for attaching the ends of the tension 40 members to the wedges whereby initial tension may be given the said members.

In testimony whereof I have signed my name to this specification in the presence of two subscribing witnesses.

Dr. FRITZ EDLER von EMPERGER.

Witnesses:

KARL REHAK,
AUGUST FUGGER.
